UNITED STATES PATENT OFFICE

GEORGE HENRY WHEARY AND BENJAMIN M. HAMLIN, OF RACINE, WISCONSIN, AS-
SIGNORS TO WHEARY TRUNK COMPANY, OF RACINE, WISCONSIN, A CORPORATION
OF WISCONSIN

LUGGAGE CARRIER

Application filed April 2, 1928. Serial No. 266,802.

It is an object of this invention to provide an improved luggage carrier of the case type having a garment or wardrobe receiver of greater depth at one end than the other to effect an economy of space in that a garment is thicker where folded over a hanger and a coat is normally thicker at the shoulder and, therefore, the space heretofore wasted by forming the receiver of the same depth throughout is eliminated and put to a useful purpose.

Another object of this invention resides in the provision of an improved luggage carrier of the case type having a receiver which is open at its inner end and hinged in line with a partition defining a well in one end of the case proper, the pivot being so located that the receiver cooperating with a stop carried by the case is retained in a vertical position by the weight of the garments supported therein.

A further object of this invention resides in the provision of an improved luggage carrier of the character described in which the garment receiver by reason of its structural characteristics assures an increased combined length of the garment compartment without increasing the overall size of the case proper.

A further object of this invention resides in the provision of an improved luggage carrier of the character described which will insure the carrying of the garments in a neat and orderly fashion without becoming wrinkled.

And a still further object of this invention resides in the provision of an improved luggage carrier of the character described having an improved garment hanger and mounting means therein whereby extra space is not required for the trolley mechanism and the hangers may be readily used apart from the case.

With the above and other objects in view which will appear as the description proceeds, our invention resides in the novel construction, combination and arrangement of parts substantially as hereinafter described and more particularly defined by the appended claims, it being understood that such changes in the precise embodiment of the

hereinafter disclosed invention may be made as come within the scope of the claims.

In the accompanying drawings, we have illustrated one complete example of the physical embodiment of our invention constructed according to the best mode we have so far devised for the practical application of the principles thereof, and in which:

Figure 1 is a perspective view of a luggage carrier embodying our invention;

Figure 2 is a view, partly in section and partly in elevation, taken through Figure 1 on the plane of the line 2—2 and illustrating the garment receiver in its vertical position, and

Figure 3 is a fragmentary view taken transversely through one end of the carrier on the plane of the line 3—3 of Figure 2.

Referring now more particularly to the accompanying drawings in which like numerals designate like parts throughout the several views, 5 represents the main section of a case to which a cover or lid 6 is suitably hinged along one marginal edge, the cover being provided with conventional locking devices 7 and the main section having a handle 8.

The main section has end walls 9 and front and rear walls 10 which are provided with pairs of opposed guide members 11 and 12, the members of each pair being equally spaced from the end walls and being channeled to receive therein the side marginal edges of partition members 13 and 14, respectively, the space between the partition member 14 and the adjacent end wall 9 providing a vertical well or space 15 which forms a transverse extension for a garment or wardrobe receiving compartment 16 within a garment or wardrobe receiver 17, to be later described. The partition 13 divides the space between the partition 14 and the other end wall 9 into various article receiving compartments which are normally closed by the receiver 17 which forms an internal cover for the case.

The receiver 17 has bottom, side and end walls 18, 19 and 20, respectively, the inner end of the bottom 18 being extended beyond the side walls 19 a slight distance and curved

downwardly, as at 21, and hinged to the marginal edge of the partition 14, as at 22. The side walls 19 increase in height from their inner ends adjacent the partition 14 to their outer ends and consequently the bottom wall 18 inclines downwardly toward the end wall 20 so that the compartment 16 is of greater depth at its outer end than at its inner end to accommodate the bulkiness normally occurring at the shoulders of the coats or other garments 23 disposed in the receiver and by the folds occurring where the garments are draped over the hangers 24. The garments placed in the receiver have their lower ends 25 extended into the well 15 and when the receiver is in its horizontal or normal position of rest the rounded portion 21 of the bottom 18 protects them against becoming creased at the point they hang over 20 into the space 15.

To pack the receiver, it is moved to its position illustrated in Figure 2 with the inner marginal edges 26 of its walls 19 at rest on cleats or stops 27 secured to the walls 10 within the space 15, the receiver being held in this position due to its weight being to one side of a line drawn vertically through the axis of the hinge 22, as will be readily apparent and when the garments are within 30 the receiver it is more securely retained in this position against accidental movement to its horizontal position. The garments are first properly draped about the hangers 24 which are then secured in the receiver and 35 when the receiver is packed it is swung to its horizontal position, care being taken that the garments do not become wrinkled. After the receiver has been moved to its horizontal position and the garments again arranged, the cover is closed, a cushion member 28 carried thereby engaging the garments to prevent their being creased or shifting within the receiver.

The receiver is supported in its horizontal position by the partitions 13 and 14, the partition 13 being of less height than the partition 14 in proportion to the inclination of the bottom wall of the receiver and by a partition 29 which is positioned transversely of the partition 13 and disposed between it and the adjacent wall 9. The partition 29 divides the space between the partition 13 and its adjacent end wall into separate compartments and is removably mounted in a manner similar to the partitions 13 and 14 by channel members 30. The upper marginal edge of the partition 29 is tapered to correspond with the bottom edge of the receiver.

The hangers 24 may be of any shape or design and each has a substantially T-shaped head 31 which engages in a substantially T-shaped slot 32 centrally formed in the wall 20 and in which they are engaged and disengaged through the open end 33, see Figure 1.

The heads 31 are also provided with hooks 34 which are pivoted thereto, as at 35, and normally are in the position illustrated in Figure 1, the hooks 34 being readily extended to provide supports therefor apart from the case.

From the foregoing description taken in connection with the accompanying drawings it will be readily apparent to those skilled in the art to which an invention of the character described appertains that we provide an improved and novel luggage carrier of the case type having a wardrobe compartment of increased length and capacity by reason of its being of greater depth at one end than the other and one which eliminates the necessity of means for maintaining the receiver in a vertical position and further that we provide a case which assures the neat arrangement of the garments and other articles and which will retain them without wrinkling.

What we claim as our invention is:

1. Readily portable hand luggage of the case type comprising a main section and a cover therefor, a readily removable partition mounted in the main section adjacent one end thereof, a wardrobe receiver hingedly connected with the partition to normally form a cover for the main section and adapted to be swung to a vertical position, the end of the wardrobe receiver opposite its hinged connection with the partition having an increased depth, and garment supporting means mounted in said deep end of the receiver and adapted to receive garments the lower ends of which are draped over the removable partition when the garment receiver is in its normal position.

2. Readily portable hand luggage of the case type comprising a main section and a cover therefor, a partition mounted in the main section adjacent one end thereof, a wardrobe receiver hingedly connected with the partition to normally form a cover for the main section and adapted to be swung to a vertical position, the end of the wardrobe receiver opposite its hinged connection with the partition having an increased depth, garment supporting means mounted in said deep end of the receiver and adapted to receive garments the lower ends of which are draped over the partition when the garment receiver is in its normal position, and means adjacent the juncture between the partition and wardrobe receiver to eliminate undue creasing of garments passing thereover.

In testimony whereof we have hereunto affixed our signatures.

GEORGE HENRY WHEARY.
BENJAMIN M. HAMLIN.
